FIG. 4

UNITED STATES PATENT OFFICE

2,055,035

FUSE PLUG

Frank G. Leavenworth, Oak Park, Ill., assignor
to William Hartman, Chicago, Ill., as trustee

Application January 10, 1935, Serial No. 1,111

2 Claims. (Cl. 200—113)

The invention relates to fuse plugs, and one of its objects is to provide an improved fuse plug which includes a liquid which will be blown out of bridging relation between the terminals when 5 an overload is placed on the circuit. Another object of the invention is to provide a fuse plug of the liquid type which, by movement or manipulation of the plug or body in which liquid is contained, can be readily restored to bridging 10 relation between the terminals for reuse.

The invention consists in the several novel features which are hereinafter set forth and are more particularly defined by claims at the conclusion hereof.

15 In the drawing which accompanies and forms a part of this specification or disclosure and in which like numerals of reference denote corresponding parts throughout the several views:

Fig. 1 is a perspective of a fuse embodying the 20 invention. Fig. 2 is a longitudinal section. Fig. 3 is a transverse section on the line 3—3 of Fig. 2. Fig. 4 is a transverse section on the line 4—4 of Fig. 2.

The fuse plug which forms the subject matter 25 of the invention is adapted to be inserted in an ordinary screw socket and comprises a hollow body or base 6 of insulating material. It also comprises a screw-shell 7 which fits around and is secured to the periphery of the body and is

30 adapted to engage the screw in an ordinary horizontally extending socket in a fuse box. A terminal stud 8 is fixed in the integral end 9 of the body 6, and an insert member 10 of insulating material is cemented in the hollow body 6 35 and closes the outer end of the chamber in the body. The screw shell 7 forms the second terminal. A terminal-forming plate or disk 11 is mounted in the hollow base and is spaced from the terminal 8. Plate 11 is electrically connected

40 by a wire 12 to the screw shell 7 and is supported in a member 13 of insulating material which is fixedly secured in the body 6 between end 9 and the insert 10. An annular space or chamber 14 is formed in member 13 between the adjacent ends of plate 8 and terminal 11 and is 45 adapted to retain a measured quantity of liquid 15, such as mercury, to form a fuse or fusible conductor between terminals 8 and 11. The inner end of insert 10 is formed with a recess

50 16 around terminal 11 and the latter is provided with a central opening 17. The current in the electric circuit passes from the terminal 8 across the liquid 15 to terminal 11 and through wire 12 to the screw terminal 7. Upon an overload in 55 the circuit, excessive flow of current through the

fluid in chamber 14 will blow the liquid 15 out of said chamber through opening 17 into recess 16. The blown out liquid 15 will then be removed from chamber 14 so that it no longer connects terminals 8 and 11, and the circuit through the 5 plug will be interrupted. From recess 16 the blown out fluid will pass into the lower portion of a chamber 18 around the member 13. Member 13 is provided with a pocket or bucket 19 which communicates with a radial port 20 which 10 leads to a duct 21 for delivering the fluid into chamber 14. Rotation of the plug in one direction will cause the pocket 19, when it traverses the mercury at the bottom, to fill with and pick up a measured quantity of mercury and when 15 the pocket approaches the top of the plug, the mercury will flow from the pocket 19 through port 20 and duct 21 into chamber 14, where it will again act as a fuse between terminals 8 and 11.

20 For heavy duty fuses, the mercury is submerged in a quantity of carbon tetrachloride, indicated at 22, to prevent burning of the mercury and the contacts by excluding oxygen and reducing combustion. This carbon tetrachloride also serves 25 quickly to condense the vapor produced by blowing the fuse after it is blown out of chamber 14. In some instances, however, this carbon tetrachloride may be dispensed with.

25 While the plug is being turned into a socket 30 in a fuse box, the member 13 will scoop a measured quantity of the mercury or liquid from the lower portion of chamber 18 and deliver it through port 20 and duct 21 into the chamber 14, wherein the mercury will be retained to serve as a fuse or 35 fusible connection between terminals 8 and 11. When the circuit is overloaded, the mercury or liquid between said terminals will be blown through opening 17 into recess 16. The mercury will be condensed in said chamber and flow into 40 the lower portion of the chamber 18 in readiness for displacement into chamber 14 for reuse. When the fuse has blown, in order to restore the mercury to chamber 14 for reuse, it is only necessary to unscrew the plug from its socket approximately a full turn and then turn the plug back 45 into the socket. The turning of the plug into the socket will automatically cause the pocket 19 to scoop the condensed mercury from the lower portion of chamber 18 and carry it to the upper portion of the plug where it will be discharged through port 20 and duct 21 into chamber 14 so it will again form a fuse between terminals 8 and 11. Chamber 14 is of such depth that it will retain the desired quantity of mercury according 50 55

- to the desired ampere capacity of conductivity, below opening 17, through which any excess of mercury delivered into said chamber will overflow to recess 16 and thence to the bottom of chamber 18. During rotation of the plug after chamber 14 has received a charge of mercury, the annular shape of said chamber will cause the desired quantity of mercury to be retained between terminals 8 and 11 until it is again blown out.
- 10 The invention exemplifies a fuse plug comprising a liquid fuse which is adapted to be blown out of place and which can be readily delivered back into operative position by the manipulation or turning of the plug itself for reuse.
- 15 The invention is not to be understood as restricted to the details set forth, since these may be modified within the scope of the appended claims, without departing from the spirit and scope of the invention.
- 20 Having thus described the invention, what I claim as new and desire to secure by Letters Patent is:

1. As a new article of manufacture, a fuse plug adapted for insertion in a horizontally extending electric screw socket and comprising a body consisting of a continuous side wall and an inner end wall of insulating material and having an open ended chamber defined by said side and end walls and a closure member of insulating material disposed in and serving to close the open end of the chamber, a terminal extending through the central portion of the end wall of the body, a screw shell extending around the side wall of the body and adapted to interfit with the screw thread of the electric socket, a terminal disposed in the chamber in spaced relation with respect to the first mentioned terminal and connected to the shell, a member of insulating material disposed in the chamber between the two terminals and 30 having a compartment for retaining a quantity of fuse forming liquid in bridged relation with

respect to the two terminals and also having an opening leading from the compartment for permitting the liquid to be blown therefrom into the chamber in the body when an overload is placed upon the plug, and means associated with said member adapted in response to rotation of the body to scoop the blown out liquid from the chamber and deliver it to the compartment to again establish electrical connection between the two terminals.

2. As a new article of manufacture, a fuse plug adapted for insertion in a horizontally extending electric screw socket and comprising a body consisting of a continuous side wall and an inner end wall of insulating material and having an open ended chamber defined by said side and end walls and a closure member of insulating material disposed in and serving to close the open end of the chamber, a terminal extending through the central portion of the end wall of the body, a screw shell extending around the side wall of the body and adapted to interfit with the screw thread of the electric socket, a terminal disposed in the chamber in spaced relation with respect to the first mentioned terminal and connected to the shell, a member of insulating material disposed in the chamber between the two terminals and having an annular compartment extending transversely of the plug for retaining a quantity of fuse forming liquid in bridged relation with respect to the two terminals and also having an opening leading from the center of the compartment for permitting the liquid to be blown from the compartment into the chamber when an overload is placed upon the plug, and a scoop formed integrally with the member and adapted in response to rotation of the body to scoop the blown-out liquid from the chamber and deliver it back to the compartment to establish electrical connection between the two terminals.

FRANK G. LEAVENWORTH.
